COMBINED DIAL AND HANDS FOR TIMEPIECES

Marcel-Jacques Bloch, La Chaux de Fonds, Switzerland

Application July 25, 1955, Serial No. 37,108

Term of patent 3½ years

(Cl. D42—1)

FIG. 1

FIG. 2

FIG. 3

Fig. 1 is a front elevational view of a combined dial and hands for timepieces, showing my new design;

Fig. 2 is a view similar to Fig. 1, showing the hands in a different position, and

Fig. 3 is a side elevational view thereof.

I claim:

The ornamental design for a combined dial and hands for timepieces, as shown.
